UNITED STATES PATENT OFFICE

LORENZO J. DRIGGS, OF ALTOONA, PENNSYLVANIA

MINE VENTILATING APPARATUS

Application filed January 30, 1932. Serial No. 589,943.

This invention relates to a mine ventilating apparatus and has for its primary object to provide, in a manner as hereinafter set forth, an apparatus of this character embodying a novel construction, combination and arrangement of parts through the medium of which a ventilating fan may be utilized either to draw air from the mine or drive air into said mine.

10 Other objects of the invention are to provide a mine ventilating apparatus of the character described which will be simple in construction, strong, durable, efficient and reliable in operation and which may be manufactured and installed at low cost.

15 All of the foregoing and still further objects and advantages of the invention will become apparent from a study of the following specification, taken in connection with 20 the accompanying drawings wherein like characters of reference designate corresponding parts throughout the several views, and wherein:—

25 Figure 1 is a view in horizontal section through an embodiment of a ventilating apparatus constructed in accordance with the present invention.

30 Figure 2 is a view in horizontal section through the apparatus showing the same operating to drive air into the mine.

35 Figure 3 is a vertical transverse sectional view taken substantially on the line 3—3 of Figure 1, looking in the direction indicated by the arrows.

40 Figure 4 is a view in vertical longitudinal section through a portion of the flume showing, in side elevation, the control unit.

45 Figure 5 is a detail view showing a means for actuating the control unit.

50 Referring now to the drawings in detail, it will be seen that the embodiment of the invention illustrated comprises a fan casing 1 which communicates with an end portion of a flume 2 through a substantially centrally located opening 3. The opening 3 constitutes the air intake of the casing 1. The casing 1 is provided with an air outlet opening 4 to the atmosphere which is controlled by a door 5.

55 A shaft 6 is mounted for rotation in the

casing 1 and extends through the opening 3, through the flume 2 and projects through the outer side wall of said flume and has fixed on its outer end a pulley 7 for connection with a suitable source of power through the medium of a belt (not shown). A centrifugal fan 8 is fixed on the shaft 6 for operation in the casing 1.

60 A by-pass 9 communicates with the casing 1 at a point between the fan 8 and the outlet opening 4 of said casing through an opening 10 which is controlled by a door 11. One end of the by-pass 9 communicates with the flume 2 at a point between the opening 3 and the mine, said one end being controlled by a door 12. Mounted for operation in the flume 2 on one side of the opening 3 and between said opening 3 and the door 12 is a control door 13. On the other side of the opening 3 the flume 2 is adapted to communicate with the atmosphere through an opening 14 which is controlled by a door 15.

65 Rotatably mounted on the shaft 6 for operation in the flume 2 is an air control unit 70 or guide which is designated generally by the reference numeral 16 and which comprises an elbow or arcuate conduit 17 having one end registering with the opening 3 in the casing 1, said one end having an external flange 18 abutting the casing 1. An annulus 19 of substantially arcuate cross section is fixed on the casing 1 in the flume 2 and is engaged over the flange 18. Mounted in the elbow or conduit 17 are the arcuate guide vanes 20 of a curvature corresponding to the curvature 80 of said elbow or conduit.

75 The control unit 16 further includes a gear or toothed disk 21 which is journaled on the shaft 6 adjacent the outer wall of the flume 2 to which the elbow or conduit 17 is rigidly secured in any suitable manner. A hand crank 22 is mounted for rotation in the outer wall of the flume 2 and has fixed thereto a gear 23 which is engaged with the gear 21. If desired, the gear 21 may be in the form 90 of a segment and suitable means provided for limiting rotation thereof in opposite directions to substantially one-half of a revolution.

100 In use, when it is desired to utilize the fan

to draw air from the mine, the various control doors are disposed as seen in Figure 1 of the drawings. The fan 8 will then draw the air from the mine through the flume 2, through the opening 3 into the casing 1 and said air will be expelled to the atmosphere through the outlet opening 4. When it is desired to drive air into the mine, the various control doors are disposed as seen in Figure 2 of the drawings and the air is drawn into the flume 2 from the atmosphere to the opening 14, through the opening 3 into the casing 1, into the by-pass 9 through the opening 10 and then passed into the flume 2 and is driven to the mine. Of course, when the air is to be driven into the mine, the control unit 16 is disposed in the position shown in Figure 2 of the drawings and when the air is to be drawn from the mine, said control unit is reversed to occupy the position shown in Figure 1 of said drawings. Actuation of the control unit 16 is accomplished through the medium of the crank 22 and the gears 21 and 23.

The unit 16 together with the annulus 19 which constitutes a guide prevent eddying of the air in the flume 2 and also after said air has entered the central portion of the casing 1, thereby materially increasing the efficiency of the fan 8. This constitutes the most important and desirable feature of the invention.

It is believed that the many advantages of a ventilating apparatus constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

1. A ventilating apparatus comprising, in combination, a flume, a casing communicating with the flume, a fan operable in the casing for drawing air from the flume into the casing, control means for selectively causing the air to be drawn into the casing from different directions into the flume, said means including an arcuate conduit mounted for rotation in the flume and having one end communicating with said flume and its other end communicating with the casing, said means further including arcuate guide vanes in the conduit, and means for actuating the control means, the second named means comprising a gear fixed to the conduit, a crank mounted for rotation on the flume, and a gear fixed to the crank and engaged with the first named gear for operatively connecting the crank thereto.

2. A ventilating apparatus comprising, in combination, a flume, a casing having an opening therein establishing communication between said casing and the flume, a fan operable in the casing, said fan being adapted to draw air through the flume into the casing, an arcuate conduit mounted for rotation in the flume and having one end communicating with the flume and its other end communicating with the opening, means for shifting the conduit for causing the air to be drawn into the casing from different directions in the flume, and an annulus of substantially arcuate cross section mounted in the flume coaxially with the opening and immediately adjacent said opening, said annulus constituting an air guide.

3. A ventilating apparatus comprising, in combination, a flume a casing having an opening therein establishing communication between said casing and the flume, a fan operable in the casing, said fan being adapted to draw air through the flume into the casing, an arcuate conduit mounted for rotation in the flume and having one end communicating with the flume and its other end communicating with the opening, means for shifting the conduit for causing the air to be drawn into the casing from different directions in the flume, and an annulus of substantially arcuate cross section mounted in the flume coaxially with the opening and immediately adjacent said opening, said annulus constituting an air guide, an external flange on the conduit engaged against the casing, the annulus encircling the conduit and being engaged with the flange.

4. A ventilating apparatus comprising, in combination, a flume, a casing having an opening therein establishing communication between said casing and the flume, a fan operable in the casing, said fan being adapted to draw air through the flume into the casing, an arcuate conduit mounted for rotation in the flume and having one end communicating with the flume and its other end communicating with the opening, means for shifting the conduit for causing the air to be drawn into the casing from different directions in the flume, and an annulus of substantially arcuate cross section mounted in the flume coaxially with the opening and immediately adjacent said opening, said annulus constituting an air guide, an external flange on the conduit engaged against the casing, the annulus encircling the conduit and being engaged with the flange, and spaced, arcuate guides fixed in the conduit.

In testimony whereof I affix my signature.

LORENZO J. DRIGGS.
